ATTORNEY.

UNITED STATES PATENT OFFICE.

JOHN KROPACZ, OF CALGARY, ALBERTA, CANADA.

DESIGN FOR A WRENCH.

57,676.

Specification for Design.

Patented Apr. 26, 1921.

Application filed October 30, 1920. Serial No. 420,823. Term of patent 7 years.

To all whom it may concern:

Be it known that I, JOHN KROPACZ, a citizen of Poland, residing at Calgary, in the Province of Alberta and Dominion of Canada, have invented a new, original, and ornamental Design for a Wrench, of which the following is a specification, reference being had to the accompanying drawing, forming part thereof.

The figure is a view in perspective of a wrench, showing my new design.

I claim:

The ornamental design for a wrench, as shown.

JOHN KROPACZ.

Witness:

W. M. FRADGH.
